UNITED STATES PATENT OFFICE.

KARL MAU, OF FORSTHAUS KOLLHOF, NEAR PUTBUS, GERMANY.

AUTOMATIC FIREARM WITH SLIDING BARREL AND A BACK-SIGHT BAR CARRYING THE FORESIGHT.

1,100,596.

Specification of Letters Patent. Patented June 16, 1914.

Application filed February 6, 1914. Serial No. 817,065.

To all whom it may concern:

Be it known that I, KARL MAU, subject of the King of Prussia, residing at Forsthaus Kollhof, near Putbus-on-the-Rügen, 5 Germany, have invented certain new and useful improvements in Automatic Firearms with Sliding Barrel and a Back-Sight Bar Carrying the Foresight, of which the following is a specification.

10 This invention relates to an automatic fire arm with sliding barrel and a back-sight bar carrying the foresight.

In connection with the known fire arms of this type, the back-sight bar is firmly 15 soldered to the barrel. This arrangement has several disadvantages. First of all, the weight of the masses moved to and fro when firing is increased by the back-sight bar, so that a considerable surplus of work is im-

20 posed upon the cartridge during the short time of its function and also upon the forwardly propelling spring. During the movements of the barrel, which, in connection with this arrangement, the back-sight

25 bar must follow, the eye of the marksman, which observes these movements, is disturbed and above all things by the moving foresight on the front end of the back-sight bar. The heating of the barrel due to the 30 firing is rapidly transmitted to the back-sight bar connected to the barrel, so that a dazzling of the eyes takes place, which interferes with the aiming.

Now the invention consists essentially in 35 that the backsight bar is supported on the receiver and connected to the barrel in such a manner that the back-sight bar does not participate in the movements of the barrel.

The back-sight bar covers the barrel like 40 an umbrella and prevents the eye of the marksman being interfered with. As the back-sight bar does not move with the barrel, no additional load is imposed on the cartridge and the forwardly propelling 45 spring. In connection with this arrangement the back-sight bar may be formed of thin spring-steel, so that the total weight of the fire arm is only slightly increased.

The invention is shown in the accompanying 50 drawing by way of example.

Figures 1 and 2 are side elevation and plan respectively of a self-loading gun constructed according to this invention. Figs. 3 and 4 are side elevation and plan respec-

tively of the back-sight bar only. Another 55 modification of the invention is shown in Figs. 5-9. Figs. 5 and 6 are elevation and plan respectively of the front part of the fire arm with the back-sight bar. Fig. 7 represents the removed back-sight bar on an 60 enlarged scale, as seen from below. Fig. 8 is a section taken on line A-B of Fig. 7, and, Fig. 9 is an elevation of the barrel with the back-sight bar removed.

In the modification according to Figs. 1-4, 65 a guide-bar *h* is secured to the front end of the barrel *l*. The back-sight bar *a*, which carries the foresight *e* in front, embraces the said guide-bar *h* with its correspondingly enlarged flanged front end *f* and also the 70 barrel *l* with a clamp-like member *b* formed in the middle.

The rear part of the back-sight bar is provided with abutments *c* engaging in recesses of the receiver, also with two lateral 75 clamps *d*, which bear resiliently behind the front ribs of the receiver, so that the back-sight bar can be easily removed from the receiver.

The back-sight bar may be slipped over 80 the barrel in front and when slipped over, it is then completely secured in position. It can also be readily interchanged so that when hunting, a barrel with a wide bore 85 may be replaced by a barrel with a narrow bore without using special tools.

In order to adapt the back-sight bar to the different lengths of barrels, it can be made according to the constructional form shown in Figs. 5-9. According to this modification, the back-sight bar is formed of two parts *a*¹ *a*², the part *a*¹ being fixed or detachably mounted on the receiver by means of abutments *c* and clamps *d* in a similar manner to the first constructional form. 90 The other part *a*² of the back-sight bar is preferably bent out of sheet steel in *U* form and embraces the front end of the part *a*¹ (Fig. 8) of the bar, also two guide-bars *h*¹ *h*² (Fig. 9) secured to the barrel. The back-sight bar is bent together at these embracing or engaging points so that three guide-paths *f*¹ *f*² *f*³ are formed on the back-sight bar (Fig. 7).

For the purpose of connecting the two 105 parts *a*¹ *a*² of the back-sight bar, there is provided on the front part *a*², a spring plate *i* having holes in which pins *k* engage, the

said pins being mounted on the underside of the rear part a^1 of the back-sight bar (Figs. 7 and 8).

If the back-sight bar adjusted for a certain barrel length is to be used for a barrel of another length, the locking plate i is depressed, so that the pins k pass out of the holes, the front part a^2 of the back-sight bar is moved on the rear part a^1 and the holding pins k are allowed to engage in the holes of the locking plate i at a suitable point.

The whole barrel length can thus always be used as sight path.

15 I claim:—

1. In an automatic firearm, the combination with the sliding-barrel and receiver thereof, of a sight-bar having a fixed engagement with said receiver and a sliding engagement with said sliding-barrel, and sighting means carried wholly by said sight-bar.
- 20 2. In an automatic firearm, the combina-

tion with the sliding-barrel and the receiver thereof, of a sight-bar, sighting means carried wholly by said sight-bar, supporting means on said sliding-barrel having a sliding-fit with said sight-bar and means providing a fixed support for said sight-bar on said receiver.

3. In an automatic firearm, the combination with the sliding-barrel and the receiver thereof, of a sight-bar having a fixed engagement with said receiver and a sliding support on said sliding-barrel, and sighting means carried solely by said sight-bar, said sight-bar consisting of sections adjustably locked together to permit the use of said sight-bar on barrels of different lengths.

In testimony whereof I have affixed my 40 signature in presence of two witnesses.

KARL MAU.
